CONVERSION ARRANGEMENT FOR
SUCTION CLEANERSRalph C. Osborn, Bloomington, Ill., assignor to
Eureka Williams Corporation, Detroit, Mich.,
a corporation of Michigan

Application March 19, 1947, Serial No. 735,592

3 Claims. (Cl. 15—333)

1

This invention relates to suction cleaners and has particular reference to certain new and useful improvements by means of which a suction cleaner of the floor type may be converted for off-the-floor cleaning operations.

Conversion arrangements for converting floor cleaners of the vertical motor type for off-the-floor cleaning operations heretofore suggested have been and are unsatisfactory because such arrangements do not permit the floor cleaner to be pulled around on the floor by means of the hose attached thereto when the cleaner is arranged for off-the-floor cleaning operations and also because such arrangements have not effectively shut off the flow of air from the floor nozzle to the fan.

According to the present invention a floor cleaner of the vertical motor type is provided with a centrally located converter port above the nozzle at the front of the cleaner, such port being connected to the suction air passageway between the nozzle and the fan for receiving a converter element to convert the cleaner for off-the-floor cleaning operations.

A converter element (not shown) is insertable through the port into the suction air passageway so as to shut off the communication between the nozzle and the fan and has provisions to accommodate the belt which extends through the passageway and interconnects the agitator arranged in the nozzle and the motor for driving the agitator during the operation of the motor. Nozzle elevating means are movably mounted on the cleaner body for movement between a retracted position above the bottom edge of the front wheels and a projected position below the lower edge of the front wheels, such nozzle elevating means being operable to elevate the nozzle and agitator to an inoperative position relative to the surface covering.

In the form of the invention illustrated the converter port is provided with a cover and a foot operated pedal is connected to the nozzle elevating means and the converter port cover for actuating the same. The converter port cover and nozzle elevating means are interconnected in such manner that the cover may be opened without effecting movement of the elevating means, and so that closing of the cover, with the elevating means in the projected position, will move the elevating means to its retracted position.

Principal objects of the invention therefore are to provide:

A new and improved conversion arrangement for floor cleaners which is arranged to elevate the nozzle and the agitator of the cleaner to an in-

2

operative position relative to the surface covering.

A new and improved conversion arrangement for floor cleaners of the vertical motor type in which means are provided in addition to the normal floor wheels of the cleaner for elevating the nozzle and the agitator to an inoperative position relative to the surface covering.

A new and simplified conversion arrangement particularly adapted for floor cleaners of the vertical motor type in which a converter port cover and a nozzle and agitator elevating means are arranged to be actuated by a foot operated pedal.

Other and further objects of the invention will be apparent by reference to the accompanying drawings of which there are two sheets which, by way of illustration, show the embodiment and the principles thereof and what I now consider to be the best mode in which I have contemplated applying these principles. Other embodiments of the invention embodying the same or equivalent principles may be used and structural changes may be made as desired by those skilled in the art without departing from the present invention and the purview of the appended claims. I also contemplate that of the several different features of my invention, certain ones thereof may be advantageously employed in some applications separate and apart from the remainder of the features.

In the drawings:

Fig. 1 is an elevational view of a cleaner embodying the invention;

Fig. 2 is an enlarged fragmentary longitudinal sectional view of the cleaner with parts broken away;

Fig. 3 is an enlarged fragmentary view taken along the staggered line 3—3 of Fig. 2 and with the cleaner arranged for on-the-floor cleaning operations;

Fig. 4 is a fragmentary view similar to Fig. 2 showing one step in the process of converting the cleaner for off-the-floor cleaning operations; and

Fig. 5 is another fragmentary view similar to Fig. 4 showing the nozzle and agitator elevated and the converter port cover in its open position for receiving a converter element.

50 A suction cleaner embodying the invention has a body indicated generally at 30 with a nozzle 31 at the forward end thereof, an agitator 29 operatively associated with the nozzle, and front and rear wheels 34 and 32 supporting the body

55 for movement on a surface covering indicated by the line 35 with the nozzle and agitator operatively positioned relative to the surface covering.

The cleaner further includes a handle 36 pivotally mounted on the cleaner body for maneuvering the cleaner and a bag 38 arranged to collect the dirt picked up by the cleaner and to separate such dirt from the air which flows through the cleaner.

A suction creating fan 40 is provided with an air inlet 42 connected by a suction air passageway 44 with the interior of the nozzle 31. An electric motor 46 is arranged for driving the fan and has a shaft 48 which extends through the fan chamber and the inlet 42 thereto. A pulley 50 is secured to the motor shaft 48 and a flexible elastic belt 52 drivingly connects the pulley 50 and the agitator 29 for rotating the same about its horizontal axis during the operation of the motor. The nozzle 31 is provided with an elongated horizontally disposed nozzle mouth 54 presented toward the surface covering 35 and arranged so that during operation of the fan 40 air will flow into the nozzle through the mouth 54 thereof and lift the surface covering 35 up against the mouth 54 of the nozzle where it is acted on by the agitator 29. The agitator is rotatable about its horizontal axis and arranged so that brush elements 56 thereon will beat and/or sweep the surface covering suspended against the nozzle mouth 54.

The body is provided with a centrally located converter port 60 above the nozzle 31 and at the front of the cleaner, such port being connected to the suction air passageway 44 for receiving a converter element not shown. The converter port 60 may be rectangular in cross section and shaped to receive the inserted end of the converter element, the end of the converter having a cross section the same as that of the port 60 and having a sliding fit in the port.

The converter element may be similar in construction and operation to that shown in the application of Harry B. White for suction cleaners, Serial No. 486,633 filed May 12, 1943, now Patent No. 2,416,786, issued March 4, 1947. The converter element forms an air conducting member and at its outer end is adapted to detachably receive a flexible hose.

The converter port 60 is normally closed when the cleaner is arranged for on-the-floor cleaning operations by a cover 200 pivoted to the cleaner body at 202 and arranged for opening and closing the port 60.

The cleaner is provided with a nozzle elevating means including a floor engaging wheel 204 which is normally positioned above the lower edge of the front floor wheels 34 as shown in Fig. 2. The wheel 204 is rotatable on an axle 206 carried by a fork 208 which in turn is carried on an arm 210 of a plate 212 which is rotatably mounted on a stationary shaft 214. The shaft 214 is suitably mounted in a fixed position on the cleaner. A compression coil spring 216 connected by a pin 218 to the rear wall of the nozzle 31 and by a pin 220 to the edge of the plate 212 normally positions the plate 212 and the wheel 204 in its retracted position as shown in Fig. 2.

A foot operated pedal 226 positioned at the side of the cleaner toward the rear thereof is mounted upon one end of a lever 228 which is pivoted on a lug 230 on the under side of the cleaner by means of a pin 232. The other end of the lever 228 has a cross pin 234 secured thereto. This pin 234 projects through slot 236 in the plate 212. The slot 236 as arranged in Fig. 2 extends somewhat horizontally so that when the pedal 226 is depressed as by stepping on it,

the pin 234 reacting on the edge of the slot in the plate 212 will shift the plate 212 from the position illustrated in Fig. 2 to that illustrated in Fig. 4, thereby shifting the nozzle elevating wheel 204 to its projected position below the front wheels 34 to elevate the nozzle to an inoperative position relative to the surface covering.

The spring 216 initially resists and is compressed by this rotary movement of the plate 212, but after the pin 220 crosses the line between the pin 218 and the axle 214 the spring 216 will expand and react on the rotary plate 212 to shift and position it as illustrated in Figs. 4 and 5.

A projection 240 on the plate 212 forms a stop which is arranged to engage the wall 242 forming the under side of the fan chamber so as to limit rotation of the plate 212 in a counterclockwise direction. The spring 216 however normally maintains the plate 212 and the wheel 204 in the position as shown in Figs. 4 and 5 after the plate 212 is rotated a sufficient amount. The plate 212 is provided with a slot 244 through which one end 246 of a link 248 extends, the other end 250 of the link 248 having an articulated connection at 259 with an arm 252 of the cover 200. A spring 254 coiled around the upper end of the link 248 and reacting against the arm 252 biases the link 248 in a counterclockwise direction about its pivotal connection with the arm 252. The end 246 of the link is free to slide lengthwise in the arcuate slot 244 so that the cover 200 may be opened when the nozzle elevating means is arranged as shown in Fig. 2. The hood 260 may be relieved adjacent the edge of the cover 200 so that the edge of the cover may be engaged by a finger for shifting it to its open position, if desired, independently of shifting of the nozzle elevating wheel to its projected position as shown in Figs. 4 and 5.

The pin 234 also extends through a slot 262 in a lever 264 which is rotatable on the shaft 214 and arranged between the plate 212 and the lever 228. Upon operation of the pedal 226 to shift the plate 212 from the position shown in Fig. 2 to that shown in Fig. 4, the lever 264 will be shifted from the dotted line position as shown in Fig. 2 to that as shown in Fig. 4. The lever 264 includes a finger 266 which projects beyond the slot 244 in the plate 212 and is arranged to engage the end 246 of the link 248 which extends through the slot 244 whereby upon further depression of the pedal 226, that is, movement thereof from the position as illustrated in Fig. 4 to that illustrated in Fig. 5, the lever 264 will be shifted so that the finger 266 thereof will engage the end 246 of the link 248 and shift the same so as to open the cover 200 as shown in Fig. 5.

When the cover 200 is closed and the nozzle elevating means is in its retracted position the spring 254 is arranged to bias the end 246 of the link 248 into a notch 280 formed in the plate 212 on one side of the slot 244. However, starting with the parts positioned as shown in Fig. 2, when the pedal 226 is depressed the end 246 of the link 248 will ride out of the notch 280, since the notch 280 is so arranged, when the plate 212 is in the position of Fig. 2, that the upper edge thereof will cam the end 246 out of the notch upon rotation of the plate 212 in a counterclockwise direction. This will permit the nozzle elevating means to be shifted to its projected position as shown in Fig. 4 without opening the cover 200 or, conversely, permits the cover 200 to be

opened without shifting the nozzle elevating means to its projected position. Upon further depression of the foot pedal the arm 266 will by engagement with the end 246 of the link 248 move the link 248 to the position shown in Fig. 5 whereupon the end 246 when it arrives opposite the notch 280 will drop into the notch and hold the cover 200 in its open position.

A torsion spring 284 reacting on the lug 230 and the lever 228 biases the pedal 226 towards its position as shown in Fig. 2, so that when the pedal 226 is released it will return to its position as shown in Fig. 4. This however will not retract the nozzle elevating means or close the cover as the pin 234 will merely move to the lower end of the slot 236. Such movement however will shift the lever 264 back to its position as shown in Fig. 4.

With the converter port 60 open the converter may be inserted therein and the cleaner is ready for off-the-floor cleaning operations. Upon removal of the converter from the port 60, closing of the converter port cover 200 by pushing it downwardly against the edge of the port will cause the nozzle elevating means to be shifted to its retracted position, since the end 246 of the link 248 is in the slot 280 and since with the slot 280 arranged as shown in Fig. 5, the end 246 of the link 248 will not slip out of the notch 280 until after the plate 212 has been rotated in a clockwise direction to a point where the pin 220 is above the line between the pin 218 and the shaft 214 whereupon the spring 216 will shift the plate 212 and the wheel 204 to the position as shown in Fig. 2.

From the foregoing it will be evident that I have provided an arrangement wherein the converter port cover may be opened and the nozzle elevated by a single operation of depressing the pedal 226, whereby upon insertion of the converter the cleaner is ready for off-the-floor cleaning operations. It will also be apparent that upon removal of the converter from the port 60 the cleaner may be arranged for on-the-floor cleaning operations merely by closing the converter port cover 200 which will shift the nozzle elevating means to its retracted position.

The arrangement also permits the converter port cover 200 to be opened without shifting the nozzle elevating means to its projected position merely by manually engaging the cover 200 and shifting it to its open position whereupon the converter may be inserted into the port and the cleaner is then ready for off-the-floor cleaner operations. When the cleaner is arranged on a hard surface such as a wood floor or linoleum there is no necessity of raising the nozzle and the agitator since their proximity to the hard floor will not make any difference as the agitator is spaced above the floor when the cleaner is setting on a hard surface.

While I have illustrated and described a preferred embodiment of my invention, it is understood that this is capable of modification, and I therefore do not wish to be limited to the precise details set forth, but desire to avail myself of such changes and alterations as fall within the purview of the following claims.

I claim:

1. A suction cleaner having a body with a nozzle at the forward end thereof, front and rear wheels normally supporting said body for movement on a surface covering with said nozzle operatively positioned relative to said surface covering, a surface covering agitator operatively

associated with said nozzle for operation on said surface covering, a suction creating fan, a motor for driving said fan, a suction air passageway between said fan and nozzle, a belt in said suction air passageway between said motor and agitator to operate the latter, said body having a converter port above said nozzle and connected to said suction air passageway for receiving a converter element to convert the cleaner for off-the-floor cleaning, a cover movably mounted on said body and arranged for closing or opening said port, nozzle elevating means movably mounted on said cleaner relative to said wheels and operable for elevating said nozzle and agitator to an inoperative position relative to said surface covering and foot pedal means connected to said converter port cover and to said elevating means for operating said elevating means to elevate said nozzle and agitator and to move said converter port cover to its open position.

2. A suction cleaner having a body with a nozzle at the forward end thereof, an agitator operatively associated with said nozzle, front and rear wheels supporting said body for movement on a surface covering with said nozzle and agitator operatively positioned relative to said surface covering, a suction creating fan, a motor for driving said fan, a suction air passageway between said fan and nozzle, a belt in said suction air passageway between said motor and agitator to operate the latter, said body having a converter port above said nozzle and connected to said suction air passageway for receiving a converter element to convert the cleaner for off-the-floor cleaning, a cover movably mounted on said body and arranged for closing or opening said port, means movably mounted on said cleaner body and movable relative to said front wheels between a retracted position above the bottom of said front wheels and a projected position below a line extending between the bottom of said front wheels, said means upon movement to said projected position elevating said nozzle and agitator to an inoperative position relative to said surface covering and foot operated pedal means mounted at the side of said body and connected to said converter port cover and to said elevating means for shifting said elevating means to said projected position and said converter port cover to its open position.

3. A suction cleaner according to claim 2 including means interconnecting said converter port cover and said elevating means, said means being constructed and arranged in such manner that said converter port cover may be opened without effecting movement of said elevating means, and closing of said cover, when said elevating means is in said projected position, effects movement of said elevating means to said retracted position.

RALPH C. OSBORN.
